UNITED STATES PATENT OFFICE.

ELWOOD B. AYRES, OF PHILADELPHIA, PENNSYLVANIA, ASSIGNOR TO PROCTOR & SCHWARTZ, INCORPORATED, OF PHILADELPHIA, PENNSYLVANIA. A CORPORATION OF PENNSYLVANIA.

FAN.

Application filed September 26, 1921. Serial No. 503,165.

To all whom it may concern:

Be it known that I, ELWOOD B. AYRES, a citizen of the United States, residing in Philadelphia, Pennsylvania, have invented 5 certain Improvements in Fans, of which the following is a specification.

The object of my invention is to construct the hub of a fan in such a manner that the blades can be secured to the fan so that the 10 fan can be used as a right or a left hand fan.

The invention is especially adapted for use in connection with circulating fans of driers, when it is desired to have some of the fans right hand and others left hand, although it will be understood that the invention can be used in the general construction 15 of fans.

In the accompanying drawings:

Fig. 1 is a side view of a fan hub, showing 20 the blades in dotted lines; and

Fig. 2 is a face view, showing the hub in full lines and the blades in dotted lines.

1 is the hub. 2 are the blades, which are secured to the hub. In the present instance, 25 there are six blades and the hub has twelve surfaces to which the blades can be attached. The surfaces 3 are arranged at one angle and the surfaces 4 are arranged at an opposite angle. The surfaces 3 alternate with the 30 surfaces 4, as shown. These surfaces, or sections, project from the extended hub proper 5, which has set screws, in the present instance, by which it is secured to a shaft. The hub has a key-way 7 so that it can be keyed 35 to the shaft.

In the drawings, the blades 2 are shown secured to the surfaces, or sections, 3 of the

hub. They may be secured by means of bolts, rivets, or other fastenings.

When the shaft is turned in one direction, 40 the blades force the air forward, but, when the shaft is reversed, the blades withdraw the air in the opposite direction. By locking the blades on the sections 4 instead of the sections 3, the shaft can be reversed and the air 45 will flow in the same direction as hereinbefore described. The details of the construction of the hub of the fan may be altered without departing from the essential features of the invention. The hub may be 50 made of cast or of wrought metal, as desired. While a six-bladed fan is shown, the number of blades may be varied without departing from the spirit of the invention.

I claim:

1. The combination in a fan, of a hub; a series of blades, the hub having two series of radiating surfaces, one series alternating with the other, and one arranged at an angle to the other; and means for securing the 60 blades to either of said sets of surfaces.

2. The combination in a fan, of a hub section having a hub proper arranged to be secured to a shaft, said hub section having a series of radiating surfaces, one surface being at an angle to the other, said surfaces alternating with each other; a series of blades arranged to be secured to one series of surfaces; and means for securing said blades to said surfaces, the whole being so arranged 65 that the fan can be used as a right or a left hand fan.

ELWOOD B. AYRES.
